DESIGN FOR AN AIR FILTER

Melroy Sinclair, Maplewood, Mo.

Application January 15, 1940, Serial No. 89,476

Term of patent 14 years

To all whom it may concern:

Be it known that I, Melroy Sinclair, a citizen of the United States, residing in Maplewood, St. Louis County, State of Missouri, have invented a new, original, and ornamental Design for an Air Filter, of which the following is a specification, reference being had to the accompanying drawing forming part thereof, in which the figure is a perspective view of an air filter embodying my new design.

The side of the article illustrated not shown, is substantially identical with the side shown, and the back not shown, is closed.

I claim:

The ornamental design for an air filter, substantially as shown and described.

MELROY SINCLAIR,
